UNITED STATES PATENT OFFICE.

CHARLES H. KELLEY, OF BOSTON, ASSIGNOR TO CHARLES B. LANCASTER,
OF NEWTON, MASSACHUSETTS.

LASTING-MACHINE.

SPECIFICATION forming part of Letters Patent No. 381,019, dated April 10, 1888.

Application filed November 25, 1887. Serial No. 256,048. (No model.)

To all whom it may concern:

Be it known that I, CHARLES H. KELLEY, of Boston, in the county of Suffolk and State of Massachusetts, a citizen of the United States, 5 have invented certain new and useful Improvements in Lasting-Machines, of which the following is a specification.

My invention relates to improvements in that class of lasting-machines in which the upper-leather is stretched and folded or lasted over and upon the inner sole by mechanical appliances; and it has for its object to improve the construction and operation of such machines.

15 In the accompanying drawings I have represented at Figure 1 my present improvement in side elevation in connection with a lasting-machine of the character represented in my Patent No. 361,363. In Fig. 2 I have shown 20 in vertical section on the line xx of Fig. 1 a part of the mechanism there represented. At Figs. 3 and 4 I have represented in vertical section on the line yy of Fig. 1 the construction and operation of a certain other portion 25 of that machine in which my present invention is also embodied; and in Figs. 5 and 6 I have shown also, on an enlarged scale, details of the device, as will be afterward set forth.

In lasting-machines as heretofore constructed, wherein the edges of the upper are seized and stretched upwardly by overhanging pinchers prior to being folded in upon the last by heel, toe, and side lasting devices, it has been usual to provide these pinchers or grippers at 35 suitable intervals entirely around the edge of the upper to be lasted. I have discovered, however, that when this is done there is a tendency of the stock, especially in the shank, to be held too tightly by the pinchers, and consequently to prevent the shoe from being well lasted where the upper is thus held. By my 40 present improvement I may use pinchers or grippers around those portions of the upper where a tight holding is desirable, while at the other portions, and especially on either side of the shank of the upper, I substitute in the 45 place of such pinchers or grippers a spring extending down sufficiently so that the upper may be caught between it and the side-lasting device, and thus be gradually relaxed by the

slip or yield of the spring as the side-lasting device brings a strain to bear upon it.

Referring to the drawings, I have there represented an overhanging device embodying my present improvements adapted to co-operate 55 with the lasting devices in the operation of lasting a boot or shoe. In this device I have represented pinchers of the lazy-tongs form with operating rods and two plates adapted to be brought together to close the pinchers and 60 to be separated to open them. I provide slots b in the lower plate, B, in which the pinchers are supported, whereby I am enabled to adjust them inwardly or outwardly, and thus give to the machine a capacity for lasting a wider 65 range of shoes. This construction is best shown at Fig. 6. I have also mounted in the same plate, B, a spring, or, more properly, a pair of springs, extending downwardly to a length sufficient to meet the edge of the upper and to 70 hold it with a yielding grip against the inward pressure of the side-lasting devices. This spring is represented at C in the drawings, and I prefer to construct it of steel and of substantially the form there shown, although it is obvious 75 that the two springs, one for each side, need not necessarily be formed of one and the same piece of metal. I find in practice that by the use of this spring, which furnishes a yielding grip of the upper, instead of pinchers with an 80 unyielding or rigid grip, I obtain a slipping or gradual releasing effect, which greatly improves the character of the finished work, especially when applied, as I have represented it, at the shank.

85 A third feature of my present improvement is in the improved device for raising and lowering the upper plate relatively to the lower one, and also for raising and lowering the entire gripping attachment in the operation of 90 the machine. It has heretofore been attempted to perform this operation by means of three screw-rods, two being screw-threaded in the lower plate and connected by means of a gearing with a single operating-wheel for opening 95 and closing the pinchers and the third screw-threaded in the upper plate and provided with a separate operating-wheel for raising and lowering the pinchers. By my present improvement I greatly simplify this apparatus by dis- 100

pensing with all screw-threads and screw-threaded portions, and by substituting a single rod for the three previously described I obtain an apparatus which is also much quicker 5 and easier in its operation.

I provide a hollow post, D, attached to the lower plate, B, and passing upwardly through the plate A. Within this post (see Fig. 2) is a sliding rod, E, or presser-foot, and above it 10 is a cam-lever, F, acting upon the head of the sliding rod. By pressing this cam-lever down I can raise the gripping attachments rapidly and by a single motion, the whole sliding upwardly upon the rod, which is connected at its 15 lower end to a downhold-plate, K, of ordinary construction, as shown. Furthermore, for moving the plates A and B together and apart to operate the pinchers, I provide a two-part circular wedge-cam. (Best shown at Fig. 5.)

20 The upper portion of this wedge-cam G is secured to the hollow post D, which it surrounds. The lower portion, H, of the wedge-cam also surrounds the post, but is left to turn loosely about it upon the upper face of the plate A, 25 and is provided with a suitable operating-handle for turning it. By turning this portion H of the wedge-cam in either direction I am enabled quickly and by a single motion to separate or bring together the plates A B to open 30 or close the pinchers.

I am aware that spring-pinchers have heretofore been employed in lasting-machines; but this feature is not embodied in my present invention, because, as before stated, by the use 35 of the spring, as herein described and shown, I am enabled to do away with pinchers altogether in lasting those portions of the upper where it is not desirable that pinchers should be employed.

40 I am also aware that in lasting-machines heretofore constructed—such as are shown, for example, in Letters Patent No. 142,657 to Trask and Wheeler—a spring-rubber has been attached to the side-lasting plate for the purpose of pressing the upper up to or against the 45

last. My present invention differs from these in that I employ a spring projecting downwardly on the inner side of the upper, or that next the last, instead of on the outer side, as in the machine mentioned. With a spring constructed and arranged according to my present invention the upper when being lasted is seized between the spring on the one side and the side-lasting devices on the other side, and is thereby lasted with a yielding grip—a feature not found, so far as I am aware, in any contrivance heretofore known.

I claim—

1. In a lasting-machine, the combination, with inwardly-sliding lasting-plates, of springs, 60 substantially as described, extending downwardly on the inner side and below the edge of the upper to be lasted and adapted to hold the same with a yielding grip against the inward pressure of the slides, all substantially as set 65 forth.

2. In a lasting-machine having an overhanging gripping attachment, the improved device for raising and lowering the same, consisting of the hollow post D, the rod E, working 70 therein and bearing at its lower portion upon a downhold, and the cam-lever F, all substantially as set forth.

3. In a lasting-machine having an overhanging gripping attachment of the character described, the combination, with the upper and lower plates, A B, of the post D, secured to the lower plate and passing through the upper plate, and the wedge-cam G H, formed in two parts, one fixed to the post and the other 80 adapted to turn around the same upon the plate A, all substantially as set forth.

In testimony whereof I have hereunto subscribed my name this 22d day of November, A. D. 1887.

CHARLES H. KELLEY.
